CLAIM

The ornamental design for a breast pump as shown and described.

DESCRIPTION

FIG. 1 is a top front isometric view of a breast pump according to the claimed design;

FIG. 2 is a front view thereof;

FIG. 3 is a rear view thereof;

FIG. 4 is a right side view thereof;

FIG. 5 is a left side view thereof;

FIG. 6 is a top elevation view thereof;

FIG. 7 is a bottom elevation view thereof; and,

FIG. 8 is a top rear isometric view thereof.

The broken lines in the figures show portions of the breast pump that form no part of the claimed design.

1 Claim, 8 Drawing Sheets
